PORTABLE LECTERN

William F. Gjede, 78 Crown St.,
Winsted, Conn. 06098

Filed Feb. 7, 1969, Ser. No. 15,687

Term of patent 14 years

Int. Cl. D6—01

U.S. Cl. D29—23

FIG. 1

FIG. 2

FIG. 3

FIG. 6

FIG. 4

FIG. 5

FIG. 7

FIG. 8

FIG. 1 is a perspective view of the portable lectern in open position for use.

FIG. 2 is a top plan view of the portable lectern.

FIG. 3 is a front view of the portable lectern.

FIG. 4 is a side elevation of the portable lectern, the opposite side thereof being a mirror image of the side shown.

FIG. 5 is a back elevation of the portable lectern.

FIG. 6 is a bottom view of the portable lectern.

FIG. 7 is a perspective view of the portable lectern in partially open position.

FIG. 8 is a perspective view of the portable lectern in a substantially fully folded position for ready portability.

I claim:

The ornamental design for a portable lectern, as shown and described.
